APPARATUS FOR CONTROLLING THE SLIDE
MOVEMENT IN LONG-BED HYDRAULIC
PRESSESEarl Cannon, Rockville Centre, N. Y., assignor to
E. W. Bliss Company, Brooklyn, N. Y., a corpora-
tion of Delaware

Application October 28, 1942, Serial No. 463,604

20 Claims. (Cl. 100—71)

This invention relates to improvements in apparatus for controlling the slide movement in long-bed hydraulic presses, and more particularly relates to improved means for maintaining the slide of such a press substantially in parallelism with the press bed during the advance or downward movement of said slide despite any die or blank irregularity which might tend to induce tilting of the slide.

Any reference in the following specification and claims to "parallelism" or "non-parallelism" is intended to relate to the attitude of the press slide relatively to the bed of a press.

An important object of the present invention is the provision of improved means for automatically effecting variations in the flow of liquid to plural rams at various points along a press slide whereby to substantially compensate for initial inequalities in such flow caused by unequal resistance offered to the advance of the press slide at various points thereon. The foregoing and other objects and advantages of the invention will be apparent from the following specification and from the accompanying drawings.

The invention disclosed herein constitutes improved means of achieving the above objects and the objects set forth in my co-pending application filed September 26, 1942, under Serial No. 459,854, which has issued as Patent No. 2,328,258 dated Aug. 31, 1943. The details of various component parts of the structures described herein are fully set forth in said co-pending application and therefore the description in the present application is limited to such details as are necessary to an understanding of the improvements illustrated and claimed herein.

The means disclosed in said co-pending application are chiefly mechanical means which are employed to effect compensatory transfer of liquid from a liquid supply for a ram or rams toward one end of the press slide to a liquid supply for a ram or rams toward the opposite end of the slide. The improvements of the present invention, however, are directed toward the accomplishment of said objects through electrical or pneumatic apparatus and circuits which are employed to achieve a response to non-parallelism and to control such a compensatory transfer of liquid.

For the purpose of illustrating the present invention, and without limiting the invention thereto, several embodiments thereof are shown in the accompanying drawings, in which:

Figure 1 is a perspective view of certain important parts of a preferred embodiment of the

present invention (hereinafter referred to as the "first" embodiment), and of a long-bed press on which it may be employed.

Fig. 2 is a detailed view, in end elevation, showing means employed for initiating a response to non-parallelism and for controlling certain compensating means employed as a part of the present invention.

Fig. 3 is a diagram illustrating the interconnection of parts comprising the said first embodiment of the invention.

Fig. 4 is a side elevation of a variable fulcrum lever which may be employed advantageously in the present invention.

Fig. 4A is a sectional view on the line X—X of Fig. 4.

Fig. 5 is a diagram illustrating the interconnection of parts comprising a second embodiment of the invention.

20 Referring first to the disclosures of Figs. 1-3, the press with which the first embodiment is illustrated may comprise a long-bed 11 provided in a base 12 suitably tied at its opposite ends to a crown 13 by tie rods 14 extending through 25 slide housings 15 which serve at least partially to guide a vertically reciprocating slide 16 and to suitably space apart the said crown and bed and maintain the two latter members fixedly in their proper relationship. Tie rod nuts 17 preferably are provided at the upper and lower ends (the latter are not visible in the drawing) of the said tie rods.

The slide 16 is reciprocated in a well-understood manner, by rams 18a and 18b, fixed symmetrically upon the slide, toward opposite ends thereof. These rams, as best understood from Fig. 3, may be enlarged at their upper ends to form ram pistons 19a, 19b and may be urged downwardly on their advance strokes by liquid introduced into advance chambers 20a, 20b and upwardly on their return strokes by liquid introduced into return chambers 21a, 21b. The said chambers, of the general character indicated in Fig. 3, may, of course, be suitably formed 40 within the crown 13 of the press.

Separate, substantially identical pumping systems are provided for handling the supply of liquid for operating each of the rams 18a and 18b. Describing in detail, only the said pumping system which is related to ram 18a, it comprises a continuously-acting pump 22a, suitably driven as by an electric motor (not shown). The said pump receives liquid from a supply tank 23 through pipe 24a and pumps said liquid 45 through pipe 25a into a distributing slide valve

26a which, depending upon the position of a piston 27a therewithin, directs the liquid either through a pipe 28a to the ram advance chamber 20a to move the ram 18a downwardly or through a pipe 29a to the ram return chamber 21a to move the said ram upwardly, or, through a pipe 30a, back to the tank 23, when it is desired that the ram remain substantially at rest. The mentioned liquid distribution, yielding the said ram movements, is controlled largely by the provision on the piston 27a of three enlarged portions or spools 31a, 32a and 33a and intervening neck portions 34a and 35a.

When it is desired to advance the ram 18a (i. e., move it downwardly) to advance the slide 16 toward the bed 11 and a die and blank thereon, the piston 27a is shifted, by any suitable means, to its extreme left position as shown in Fig. 3, whereupon liquid entering the valve 26a, through pipe 25a, passes around neck portion 34a, of the said piston, into pipe 28a, and thence to the ram advance chamber 20a, thereby forcing the ram 18a downwardly while liquid is exhausted from the ram return chamber 21a through pipe 29a into the valve 26a, wherein the exhaust liquid passes around neck 35a of said piston to pipe 30a which carries it to the tank 23. By shifting the piston 27a, to its extreme right position, the flow of liquid is reversed with respect to the said ram chambers thereby causing the ram 18a to 30 pursue its upward or return movement.

When it is desired to arrest the movement of the ram 18a, the piston 27a, may be moved to its mid-position, in which the several mentioned spools on said piston close off all liquid communication between the pump 22a and the ram chambers 20a and 21a. However, the liquid, continuing to be discharged by the pump 22a passes from pipe 25a into interior lateral passage 36a in the spool 32a, thence through longitudinal passage 37a into lateral passages 38a, 39a in the spools 31a and 33a, whence said liquid passes into pipe 30a which carries it to the tank 23.

In view of the similarity of the pumping systems for actuating the two rams, the foregoing description is intended to suffice for both. For this reason, the similar parts of the pumping systems are given reference characters, in the drawings and hereinafter in the specification, differing only in their suffixes, the suffix *a* being applied to parts of the pumping system related to ram 18a and the suffix *b* being applied to parts of the pumping system related to ram 18b. Both valves 26a and 26b function alike and may be constrained to function in unison by having their respective pistons tied together by extension rods 46a and 46b which preferably are adjustably coupled by a turnbuckle 41. The said pistons may be shifted within their respective valves by any suitable means to control the reciprocation of the press slide. Such means, for example, may be operated manually, electrically, by compressed air, or by hydraulic pressure.

As illustrated in the accompanying drawings, an electric solenoid 42 may suitably be connected as by a pin 43 to an end extension 44 of the piston 27a. The said solenoid is adapted, when energized, to move the pistons 27a and 27b to their left positions, as shown in the drawings, to cause downward movement of the press slide 16. Another solenoid 45 may be similarly connected to the piston 27b for moving both pistons to their right positions to cause upward movement of the press slide. The two said solenoids, of course,

are connected in suitable electric circuits for controlling the operation of the press.

The pistons 27a, 27b may be held yieldably in their mid-positions by any suitable means which, for example, may employ springs or air or hydraulic pressure. As illustrated in the accompanying drawings, a spring centering device is employed comprising a coil spring 46 which is positioned about the extension rod 46b and is compressed between washers 47 which, normally, are held against the end of said spring by collars 48 formed on or fixed on the rod 46b. A cage-like frame 49 is fixed upon some fixed part of the press or other suitable fixed support in such position, adjacent the rod 46b, that the latter passes through holes 50 in the ends of said frame, large enough to freely pass the said collars but small enough to confine the washers 47 within the said frame. Thus, when the pistons 27a and 27b are held in their left positions, as illustrated in the drawings, by the energized solenoid 42, the spring 46 is exerting compression upon the right washer 47 and the right collar 48 which, when the said solenoid is de-energized, will cause the said pistons to move to their mid-positions. A similar, but opposite action of the centering device results when the said pistons are held in their right position by the solenoid 45 and the latter is then de-energized.

Although the pumping systems for operating the rams 18a and 18b, as thus far described in detail, may be substantially identical in design, it will be appreciated that, where resistance to the advance of the slide is not uniformly distributed thereover, the different slippages in the two pumps, slight leakages, and possibly other factors, would cause the side or end of the press slide encountering the least resistance to advance ahead of the other side thereof and this uneven advance or cocking of the slide, in many instances, would become more pronounced as the slide progressed toward the end of its advance stroke. This highly undesirable functioning of the press may be substantially obviated by compensating means now to be described in detail.

An important feature of this invention is the provision of automatic and quickly responsive means for substantially equalizing the supply of liquid to the hydraulic chambers of the several rams which actuate the press slide. According to the first embodiment of the invention it is preferred to provide such means comprising a compensator pump 51 (Fig. 3) connected by a pipe 52 to the pipe 28a which carries the liquid supply to ram advance chamber 20a, and connected by a pipe 53 to the pipe 28b which carries the liquid supply to ram advance chamber 20b.

The compensator pump 51 may be a continuously acting reversible pump suitably driven as by an electric motor (not shown). The said compensator pump further is preferably provided with a pumping mechanism, which is movably adjustable by means which extend to the exterior of the pump itself, for reversing the flow of liquid through the pump and for controlling the volume of such flow. Although various types of pumps, having pumping mechanisms conforming to these preferred characteristics, may be used, a pump of the so-called "Hele-Shaw" type such as is illustrated and described in my said co-pending patent is well suited to the purposes of the invention.

As the particular control mechanism employed in the compensator pump is not an essential part of the present invention, the said pump is not

herein described in detail. It is sufficient to observe for present purposes that the flow of liquid through the pump 51 may be reversed and the volume thereof controlled by a reciprocating control member 54 which extends from the interior mechanism of said pump to the exterior thereof and is operatively connected through a lever 55 to an extension 56 of a piston 57 of an air motor 58. The said motor, as hereinafter explained, is automatically operated in such manner as to regulate the direction and volume of flow of liquid through the compensator pump 51 in order to derive a transfer of a suitable volume of liquid from the liquid supply of one of the mentioned rams to the liquid supply of the other of said rams whereby to substantially restore and maintain parallelism of the press slide during its advance movement.

The supply of air, as a driving medium, to the air motor 58, is preferably controlled by means of an air distributing valve 59 and an air release valve 60. In carrying out the present invention it is preferable to provide electrical means for operating the valves 59 and 60, which electrical means may conveniently be arranged to respond to non-parallelism of the press slide and to control the operation of the air motor 58 so that the latter may operate the control means of the pump 51 to give to the latter its desired compensating effect.

The piston 57 of the air motor 58 has two spools or piston heads 61l and 61r integrally formed therewith or fixedly secured thereupon and is arranged to reciprocate within a bore in an elongated casing 62. The said bore is of different diameters at various points therealong to form a central air chamber 63 and certain oppositely-acting air chambers located toward opposite ends of said casing, namely, balancing chambers 64l and 64r, driving chambers 65l, 65r, and drain chambers 66l and 66r. All the mentioned chambers in the air motor 58, as shown in Fig. 3, are provided with suitable ports which, in the case of the drain chambers 66l, 66r afford communication between said chambers and the free exterior air, and in the cases of the other mentioned chambers afford means of connecting the latter to a compressed air line and to the air valves 59 and 60.

Similar oppositely-acting centering sleeves 67l, 67r are accurately fitted to slide upon the piston 57 outwardly of the spools 61l, 61r and are accurately fitted to slide within annular webs 68l, 68r which separate the said balancing and driving chambers at opposite ends of the air motor. The said centering sleeves have annular flanges 69l at their outer ends for limiting the sliding movement of said sleeves.

Another pair of similar oppositely-acting sleeves 69l, 69r are accurately fitted to slide upon the piston 57 at points between the spools 61l and 61r. These sleeves have similar annular flanges 69l on their inner ends, the said flanges being arranged to work within the central air chamber 63.

The air distributing valve 59 is very similar to the hydraulic distributing valves 26a and 26b. It comprises a piston 70, having three spools 71, 72, 73 formed on or fixed thereon, and accurately fitted to slide within a bore 74 in a casing 75. The said spools define neck portions 76 and 77 on said piston. The valve 59, as shown in Fig. 3, is provided with suitable ports, which may be covered and uncovered by the spools 71, 72, 73, when the piston 70 is moved to various

longitudinal positions, and which afford means for connecting the valve 59 with the free air and with various ports of the release valve 60 and the air motor 58. The valve 59 may be provided with a centering spring 78 which operates to center the piston 70 in the same manner as the spring 46 functions to center the pistons of the hydraulic valves 26a and 26b. The piston 70 is connected to oppositely-acting solenoids 79, 80, which are connected in circuits, hereinafter described.

The air release valve 60 comprises a piston 81 having two spools 82, 83, accurately fitted to reciprocate within a bore 84 of a casing 85. The said spools define a neck portion 81a therebetween. The casing 85, as shown in Fig. 3, is provided with several ports affording means for connecting the interior of the bore 84 to free air and to pipes leading to the air motor 58 and the valve 59. The piston is normally urged toward the right by a compression spring 86 and is movable toward the left against the compression of said spring by means of a solenoid 87 which is suitably connected to said piston. The said solenoid is connected in electric circuits, hereinafter described.

In order to mechanically detect any non-parallelism of the press slide 16, a pair of vertically disposed racks 88 (see Fig. 1) are secured at their lower ends to the slide 16 toward opposite ends thereof. The said racks may be guided within suitable guides 89 fixed upon the crown 13, and when the slide descends, the racks rotate shafts 90l and 90r in common directions through the medium of step-up gears 91, which are suitably journaled upon brackets 92. The gears 91 drive pinions 93, which are keyed upon the outer ends of the shafts 90l and 90r. The two mentioned shafts are supported within brackets 94 fixed upon the crown 13.

It will readily be understood that if the slide 16 remains in parallelism with the press bed 11 during the advance stroke of the press, the described rack and pinion arrangement causes the shafts 90l and 90r to rotate to like degrees, thus causing no relative movement as between said shafts. On the other hand, if during the advance stroke of the press slide, one end of the slide advances somewhat ahead of the other end thereof causing a tilting thereof, the mentioned rack and pinion arrangement causes one of the shafts 90l, 90r to rotate to a greater degree than the other of said shafts.

Although the mentioned difference in the degrees of rotation of the shafts 90l, 90r may not be very great, means are provided in the present invention whereby such difference in rotation causes the closing of an electric circuit or circuits which control the operation of the air valves 59 and 60 which, by controlling the flow of air to the air motor 58, cause the latter to operate the control means of the compensator pump 51 whereby to substantially equalize the supply of liquid to the hydraulic chambers of the several rams which actuate the press slide.

The mentioned means for closing said circuits, as may best be understood from Figs. 1 and 2, comprise a switch plate 95 fixed upon the inner end of the shaft 90r and constrained to turn therewith, and a plurality of electric switches 96l and 96r, 97l and 97r, and 98l and 98r, arranged upon the switch plate 95 adjacent the periphery of a switch actuator 99 which is fixed upon the inner end of the shaft 90l and constrained to rotate therewith.

The several mentioned switches may be carried upon blocks 100 which may advantageously be slidable, but with a very close and tight fit, within slideways 101. Means are provided for adjusting the positions of said blocks and switches relatively to the actuator 99, comprising lugs 102 through which are threaded adjusting screws 103 which bear against the outer sides of the blocks 100 and are locked in proper adjustment by lock nuts 104. Although other suitable means may be employed for adjusting the positions of the switches, the means just described permit the positioning of the latter so that the operating plungers of the switches 96l, 96r may normally be in engagement with the actuator 99 whereby one or the other of said switches may close in response to even a slight relative movement between the switch plate 95 and the actuator 99; the switches 97l, 97r may be positioned with their operating plungers slightly spaced from the actuator 99 so that said switches may close in response to a relative movement slightly greater than that which closes switches 96l, 96r; and switches 98l, 98r may be positioned so that their operating plungers are slightly more removed from the actuator 99 than plungers of the switches 97l, 97r.

All the switches referred to are of the type which have become known as "micro-switches" and are so designed that an inward movement of their operating plungers of as little as .001 inch suffices to close a circuit through the switch, and further, are so designed that the switch plunger, after moving inwardly sufficiently to close the circuit through the switch, is capable of inward non-effective overtravel. By utilizing switches of the mentioned character in the manner described it is possible to provide that the switches 98l, 98r may be operated to close circuits therethrough while the operating plungers of the other mentioned switches are moving within their mentioned overtravel. Similarly, switch 97l may operate within the overtravel of switch 98l and switch 97r may operate within the overtravel of switch 96r.

Means are provided, in the form of a take-off drum 105 fixed upon the shaft 90r, for connecting the several mentioned switches in suitable electric circuits. As seen from the elevational showing of said drum in Fig. 3, it comprises a plurality of take-off rings 106, 107, 108, 109, 110 and 111, all insulated from each other and suitably connected interiorly of said drum to the several switches by wiring which is diagrammatically indicated in Fig. 3. The several mentioned take-off rings are each engaged by wiper contacts which are preferably mounted upon the crown 13 of the press, and, from said contacts, connecting wires extend to certain electric solenoids in a manner which is hereinafter described in connection with the operation of the apparatus.

The racks 88 preferably are split longitudinally as indicated at 88a, and the two parts of each rack are capable of relative longitudinal adjustment through the medium of suitable adjusting screws 112 carried by brackets 113 fixed upon the slide 16. By suitable adjustment of the screws 112, the parts of the racks 88 may be shifted slightly longitudinally relatively to each other whereby to eliminate all material lost motion between the teeth of said racks and the teeth of the step-up gears 91.

In practice, the parts of the described apparatus are so assembled that, when the slide 16 and the bed 11 are perfectly parallel, the switches

on the switch plate 95 and the actuator 99 are in the relative positions shown in Fig. 2. In such positions, normally open switches 96l, 96r, 97l and 97r are open, and normally closed switches 98l and 98r are closed and the pistons of the air valves 59 and 60 and of the air motor 58 are all in the positions indicated in Fig. 3 of the drawings.

If the press is open and it is desired to cause the press slide 16 to move downwardly to perform a pressing operation, the operator sets switch 114 to its "down" position, as shown in Fig. 3, thereby closing a circuit from main lead 115 (indicated as a negative lead), through switch 114, wire 116, 15 the coil of solenoid 42, main lead 117, take-off ring 106, thence by wire 118 to and through series connected, normally closed switches 98r, 98l which are connected by wire 119 to take-off ring 107 and thence to lead 120 which is indicated as 20 a positive lead. Automatic or semi-automatic means may be and usually are provided for controlling the circuits through solenoids 42 and 45, but such means are not described herein as they constitute no part of the present invention.

Upon the closing of the mentioned circuit through solenoid 42, the latter is energized and draws the pistons of the hydraulic valves 26a, 26b to their left positions as shown in Fig. 3, whereupon liquid from the pumps 22a, 22b passes 30 through the valves 26a, 26b and pipe lines 28a, 28b to ram advance chambers 20a, 20b, respectively, thus causing rams 18a and 18b to descend with the slide 16, the liquid from return chambers 21a, 21b, meanwhile, being exhausted through pipes 29a, 29b to the valves 26a, 26b and thence 35 through pipes 30a, 30b back to the tank 23.

For present purposes it may be supposed that the press contains a die or dies of such irregular vertical dimensions, or that the blank is of such a character, that the slide 16, in its downward movement, meets a greater resistance to such movement toward its right end, thus inducing, in the pump 22b, a greater slippage than is present in the pump 22a, with the result that the latter pump passes a somewhat greater volume of liquid 40 into ram advance chamber 20a than is passed into ram advance chamber 20b by the pump 22b with the result that the left side of the slide 16 tends to move downwardly ahead of the right side thereof, thus giving the slide an objectionable tilting attitude which may impair the precision of the pressing operation as affecting the blank and which, in any event, introduces very objectional friction and consequent wear in the slide guides of the press.

However, immediately upon the inception of such uneven descent and before the tilting of the press slide becomes objectionable in any practical sense, the shaft 90r rotates somewhat ahead of the shaft 90l, thus imparting to the switch actuator 99 a clockwise motion (as viewed in Figs. 1 and 2) relatively to the switch plate 95, causing the said switch actuator to depress the plunger of switch 96r sufficiently to operate the latter and thereby close a circuit from main lead 115, through wire 121, take-off ring 111, wires 122, 123, switch 96r, wire 124, take-off ring 108, wire 125, the coil of solenoid 80 and wire 126, to main lead 117. Upon the closing of the said circuit through solenoid 80, the latter is energized and draws the piston of air distributing valve 59 toward the right against the tension of spring 18 to a position in which compressed air from air line 127 may freely enter the valve 59 through pipe 128 and pass along and around neck portion 76 of the piston 70,

whence it may pass out of the valve 59 through pipe 129 into driving chamber 65^r of the air motor 58.

As will be seen from Fig. 3, the balancing chambers 64^l, 64^r are directly connected to air line 127, hence the air pressure in said balancing chambers functions normally to maintain the piston 57 of the air motor in its mid position, as shown in the drawings, by air pressure exerted on the outer ends of the sleeves 67^l, 67^r, which press at their inner ends against the spools 61^l, 61^r, respectively. However, when compressed air at the same pressure is introduced into driving chamber 65^l, in the manner just described, the force of said pressure exerted upon the left side of the spool 61^l is greater than the difference between the forces of the pressure on the left and right sides of the flange 61^l of the sleeve 67^r, hence the piston 57 is driven toward the right until the spool 61^l engages the left end of the sleeve 67^r but proceeds no further inasmuch as the force of the air pressure within the central air chamber 63, which is normally connected to air line 127 through pipe 130 and valve 60 exerts a greater force upon sleeve 67^r than the difference in the forces applied to the spool 61^l in the chamber 65^l and to the sleeve 67^r in the chamber 64^r.

The mentioned limited shifting of the piston 57 to the right in the manner just explained causes the lever 55 to turn about its fulcrum 55^a and move the control member 54 of the reciprocating pump 51 to the left, and the connection of the said control member to the said pump is such that the latter pumps liquid through pipes 53 and 52 from the primary liquid supply of ram 18^a to the primary liquid supply of ram 18^b.

This pumping action of the pump 51, resulting from the limited shifting of the piston 57 of the air motor 58 and the consequent limited control change in the compensator pump 51, may transfer sufficient liquid from one side of the press to the other to fully compensate for the pre-existing inequalities in the volumes of liquid supplied to the opposite side of the press, with the result that the slide 16 of the press is restored to parallelism with the press bed 11. While such restoration is taking place, there occurs a counterclockwise movement of the switch actuator 99 relatively to the switch plate 98 which permits switch 96^r to open, thus breaking the mentioned circuit through solenoid 80, whereupon the piston 78 of the air distributing valve 59 is restored to the mid position shown in Fig. 3 by the centering spring 78.

In the said midposition of piston 18, the spool 72 closes off pipe 128 while driving chamber 65^l of the air motor is connected to exhaust port 130 of air valve 59 through air pipe 129 and through the interior of valve 59 wherein the exhaust air from chamber 65^l may pass around neck portion 78 to said exhaust port 130 and pass through the latter to free air. Upon chamber 65^l of the air motor being connected to free air in the manner just described, the air pressure in the balancing chamber 64^r functions to move sleeve 67^r to the left, carrying the piston 57 with it back to the latter's midposition, as shown in the drawings. The said movement of the mentioned piston, of course, restores the control member 54 of the compensator pump 51 to its normal position in which the pumping mechanism of said pump, although being driven by its motor, is nevertheless not passing any liquid.

If, after the discontinuance of the pumping action of the compensator pump 51, the irregu-

larity of the die or blank causes the left side of the press slide 16 again to move ahead of the right side thereof, the described apparatus again functions in a similar manner to bring the compensator pump into play to again restore the parallelism of the press slide. This compensating action may conceivably take place a number of times during the advance of the press slide so that, during said advance, the press slide pursues an almost imperceptible rocking action. The latter action, of course, is restrained within permissible limits so that, in so far as any material considerations are concerned, the press slide is maintained in parallelism with the bed of the press during its entire advance movement.

It should be understood, of course, that if the irregularity of the die or blank is such as to cause the right side of the press slide 16 to advance slightly ahead of the left side thereof the apparatus already described effects compensation in the manner just explained, except, of course, that the switch actuator 99 operates switch 96^l instead of switch 96^r, and, as the former switch is connected through take-off ring 108 to the coil of solenoid 79, the piston of the air distributing valve 59 is moved to the left instead of to the right, so that compressed air is introduced into chamber 65^r of the air motor 58 instead of into chamber 65^l thereof, thereby causing the piston of said air motor to move toward the left, thus causing the reciprocating control member 54 of the compensating pump to move to the right whereby to cause the pumping mechanism of said pump to transfer liquid from the primary liquid supply of ram 18^b to the primary liquid supply of ram 18^a, thus restoring the parallelism of the press slide.

It may occur in practice that die or blank irregularities or other conditions may be such as to cause a more pronounced or objectionable tilting of the press slide than the permissible tilting which the compensating means thus far described is adapted to compensate. Such objectionable tilting may be of such magnitude that, if we assume the left side of the press slide to be moving in advance of the right side thereof, not only would switch 96^r be closed by the actuator 99, but the clockwise rotation of said actuator relatively to switch plate 98 would be sufficient to also close switch 97^r which, as may be seen from Fig. 3, is connected through take-off ring 110 with the coil of solenoid 87. Thus, in the event of such excessive tilting of the press slide, the solenoid 87 is energized and moves piston 81 of air release valve 60 toward the left against the compression of spring 86, causing spool 83 to close off air line 127 from communication with the interior of said valve and at the same time affording a passage permitting air from central air chamber 63 of the air motor 58 to exhaust through pipe 130 into release valve 60, whence said exhaust air passes around and along the neck portion of the piston 81 and escapes to free air through exhaust port 131.

Upon the opening of central air chamber 63 of the air motor 58 to exhaust, the sleeve 69^l which theretofore functioned as a stop limiting the sliding movement of the piston 57 to the right, becomes free to move to the right within chamber 63 thus permitting a further movement of the piston 57 to the right, in addition to the limited sliding movement previously pursued by said piston, in response to air introduced into chamber 65^l. This further movement of the piston 57 to the right causes a corresponding fur-

ther movement of the reciprocating control member 54, of the compensator pump, toward the left, thus increasing the compensating flow of liquid through the pump 51 to yield sufficient additional compensation to overcome the excessive tilting of the press slide and restore it to parallelism.

In the event that excessive tilting of the press slide occurs in which the right side of the press slide moves downwardly in advance of the left side thereof, the switch actuator 99 closes switch 97l instead of switch 97r. It will be observed, however, that both mentioned switches are connected in circuit through the coil of solenoid 87, thus, regardless of which side of the press slide is moving ahead when excessive tilting is present, the solenoid 87 is energized to shift the piston 81 of air release valve 60 toward the left, in the manner already described, to exhaust the air and relieve the pressure from central air chamber 63 of the air motor 58. Such release of pressure in said chamber permits sleeve 69r to move toward the left when the piston 57 is being urged toward the left, thereby permitting said piston to move beyond its initial limited movement, causing a corresponding increase in the movement of the reciprocating control member 54 of the compensator pump to the right so that the flow of liquid through said pump, in the proper direction, is increased sufficiently to yield the desired increased compensating effect.

Under some conditions it may be feasible to dispense with the air release valve 60. If this is done, the apparatus employed would be so adjusted that the compensator pump 51, under any anticipated operating conditions, would fully yield the compensating effect necessary to restore the parallelism of the press slide as a result of a single shift of the control member 54. However, if the compensating capacity of the compensator pump 51 is stepped up sufficiently to cause adequate compensation, in all instances, in response to the closing of only a single switch, 96l or 96r, compensation would occur very rapidly and consequently the mentioned rocking of the press slide, under some circumstances, might be objectionably rapid, and during a single advance stroke of the slide might occur so frequently as to be objectionable.

The air release valve 60 is advantageous in that, by its use, a complete stroke of the piston 57 of the air motor 58 and consequent extreme adjustment of the control member 54 of the compensator pump, is accomplished in two distinct steps rather than in one step. If excessive tilting of the press slide occurs, the mentioned two step adjustments yield the maximum compensating effect necessary to restore the press slide to parallelism. However, the tilting of the press slide, in many cases, may be compensated before becoming excessive, by the effect of only one step of compensator pump adjustment. It follows that when only the lower compensating effect, of a single step of compensator pump adjustment, is brought into play, the rocking action of the press slide is much slower and not frequent enough to be objectionable.

It may be understood from the foregoing explanation of the effects of too rapid compensation, that it is important to so correlate the movement of the piston 57 of the air motor 58 to the movement of the reciprocating control element 54 of the compensating pump that only the proper degree of compensation is obtained. In order to readily permit correlation of these

movements it is preferable to provide a variable fulcrum point for the lever 55.

Preferred means of providing a variable fulcrum point for the lever 55 are illustrated in Figs. 4 and 4a. As illustrated, the lever 55 is formed of two opposed similar side pieces 132a, 132b which are spaced apart, and the upper ends thereof are pivotally connected to opposite sides of the outer end of the reciprocating control member 54. The lower ends of said side pieces are pivotally connected at opposite sides of one end of a link 133 which is connected to the extension 56 of the piston of the air motor 58.

A bracket 133 is fixed, as by machine screws or bolts 134, upon any convenient fixed surface of the press installation located sufficiently near to the compensator pump 51 and the air motor 58 that an elongated extension 135 of said bracket may extend between the side pieces 132a and 132b. Over substantial portions of their lengths the said side pieces are slotted as at 136, and the extension 135 is slotted as at 137. A follower block 138 is threaded upon and movable longitudinally within the slot 137 by an elongated screw 139, an unthreaded portion at the lower end of which seats within a socket 140 at the lower end of the slot 137. The screw 139 is threaded over all of its length except the lower end portion just mentioned, and the upper end 141 which may be of any suitable shape for receiving a wrench to turn said screw or may, if desired, have a small hand wheel fixed thereto. The upper end of the extension 135 serves as a lug 142 through which the screw 139 extends, and lock nuts 143 are provided on said screw at each side of said lug to permit locking the said screw in position.

The follower block 138, as best seen in Fig. 4a, is provided on each side with trunnions 144 which protrude into the slots 136 in the side pieces of the lever 55. The said trunnions each fit accurately into bores of blocks 145 which are suitably formed to slide within rabbets 146 formed along the inner sides of the slots 136.

It will be observed from Fig. 4a that, except for the trunnions 144, the follower block 138 is the same width as the adjacent portions of the extension 135 and that the inner surfaces of the blocks 145 are in the same plane as the inner surfaces of the side pieces 132a, 132b. Under this arrangement the said side pieces and the blocks 145 which slide therein are free to oscillate as a part of and with the lever 55 while the follower block 138, although capable of sliding motion within the slot 137 in response to turning of the screw 139, is nevertheless restrained against any oscillating movement. It will be seen that by means of the structure illustrated in Figs. 4 and 4a the fulcrum point 55a of the lever 55 may conveniently be moved up or down, within all desired practicable limits, with respect to the lever 55 so that the action of the air motor 58 may be correlated to the action of the compensator pump 51.

The second embodiment is illustrated in Fig. 5 and parts therein, which are similar to those illustrated in Fig. 3, are given reference characters which are similar except that where in Fig. 3 the suffixes *a* and *b* have been employed in the reference characters of parts in the hydraulic systems supplying the two rams, suffixes *a*, *b*, *c* and *d* are employed in Fig. 5 in the reference characters of certain parts of the hydraulic systems supplying the four rams illustrated.

The second embodiment may best be understood by considering it as an adaptation, of the

instrumentalities employed in the first embodiment, to a long-bed hydraulic press in which four rams 18a, 18b, 18c and 18d are associated with the press slide 16 to impart the desired pressing movements to the latter. The pump 22a and hydraulic distributing valve 26a handle the primary supply of liquid to ram 18a; the pump 22b and the hydraulic distributing valve 26b handle the supply of liquid to the ram 18b; a pump 22c and a hydraulic distributing valve 26c handle the supply of liquid to the ram 18c; and a pump 22d and a hydraulic valve 26d handle the supply of liquid to the ram 18d.

Instead of employing only a single compensator pump, it is preferred, in the second embodiment, to employ two substantially similar compensator pumps 51bc and 51ad, the former being connected by suitable pipes 52bc, 53bc, between the pipes 28b and 28c which carry liquid to the advance chambers which actuate rams 18b and 18c, and the latter pump being connected by suitable pipes 52ad, 53ad, between the pipes 28a and 28d which carry liquid to the advance chambers which actuate rams 18a and 18d.

The single air motor 58 is adapted to actuate the reciprocating control members 54bc and 54ad of the two compensator pumps by connecting the levers 55bc and 55ad to opposite end extensions of the piston 57 of said air motor in the manner indicated in the drawings. A single air distributing valve 59 and a single air release valve 60 control the air supply to the air motor 58 similarly to the first embodiment.

The electrical system of the second embodiment differs from that illustrated in the first embodiment only in that two oppositely-acting solenoids are employed for independently actuating each of the hydraulic distributing valves. However, as it is necessary that the said valves function similarly and simultaneously, the solenoids 42a, 42b, 42c and 42d which function to shift the pistons of their related hydraulic distributing valves to the left, are all connected in parallel in a single circuit and the solenoids 45a, 45b, 45c and 45d which function to shift the pistons of said valves to the right are likewise connected in parallel in another single circuit. The first mentioned circuit which causes the mentioned left shifting resulting in a downward movement of the press slide 16, is closed when the switch 114 is set to its "down" position, and the second mentioned circuit which causes the mentioned right shifting resulting in an upward movement of the press slide 16 is closed when the switch 114 is set to its "up" position.

Inasmuch as the hydraulic distributing valves 26a, 26b, 26c, 26d in the second embodiment are all operated independently, each of said valves is provided with its own centering means. Each of said centering means functions exactly as the centering means described in connection with the first embodiment, the only difference being that in the second embodiment centering springs 46a, 46b, 46c and 46d are located within the casings of their related valves.

The variable fulcrum arrangement already described in detail is preferably employed in connection with both levers 55bc and 55ad. As, in any compensating movement of the press slide, the volume of compensating liquid transferred between the liquid supplies of rams 18b and 18c is much less than the volume of compensating liquid transferred between the primary liquid supplies of rams 18a and 18d, it is necessary that the rate of flow of liquid through the two com-

pensator pumps be controlled so as to give effect to the said differences in the volume of liquid transfer as between the two mentioned pairs of rams. This may easily be accomplished by varying the position of the fulcrum of each of the levers 55bc, 55ad, so that for any given stroke of the piston 57 of the air motor 58 the resulting stroke of the control member 54bc will be substantially less than the resulting stroke of the control member 54ad so that the rate of flow of liquid through the pump 51ad will be substantially greater than the rate of flow through pump 51bc. It will be seen that proper adjustment of the fulcrum points of the two mentioned levers will yield a proper rate of flow through the two compensator pumps.

In the event that the slide 16, in its downward movement, is tilting to one side or the other, one or more of the several electric switches, in the manner already fully described, will close and cause the air motor to bring the pumps 51bc and 51ad into play to cause transfer of compensating liquid between the liquid supplies to rams 18b and 18c, and between the liquid supplies to rams 18a and 18d.

It will be observed that in both modifications the switches 98l, 98r are connected in series through the take-off rings 106, 107 between the wire 120 and the main lead 111. These switches are normally closed so that in normal operation the circuit between said wire and lead is closed. The said switches 98l and 98r, as best seen from Fig. 2, may only be actuated by the actuator 99, by rotation of the latter relatively to the switch plate 95 to a greater extent than is necessary to actuate switches 97l and 97r.

Ordinarily, compensation takes place in all cases before actuation of the switches 98l and 98r occurs. However, if some part of the system were to fail, with the consequent failure of the compensating mechanism, or if for any other reason compensation should not take place and the tilting of the press slide progressed sufficiently to be objectionable or dangerous, one or the other of switches 98l or 98r would be opened by the actuator 99, thus opening the solenoid circuits which include said switches, whereupon the pistons of the several hydraulic distributing valves would assume their mid positions, thus stopping the movement of the press slide, and the piston of the air valve 59 would move to its mid position, thus centering the piston of the air motor 58 and shifting the control members of the compensator pumps to neutral or non-pumping position. Thus the switches 98l, 98r function as safety switches.

It is well known by those familiar with the art relating to hydraulic presses, that suitable means in the form of drain or by-pass ducts or clearances must be provided in certain portions of the various valves and the air motor to prevent locking thereof. Such means, however, are not essential features of the present invention and, therefore, have not been fully illustrated in the drawings.

It should be understood, of course, that the invention may be employed in presses using three or five or more rams and that the use of a compensator pump or pumps may be avoided in some installations, by adapting the electric or pneumatic apparatus, or both, to function directly with the pumps provided for supplying liquid to the several ram chambers, whereby to effect compensation directly in said pumps. The invention may be practiced in these and many other ways

without, however, departing from the substance of the invention as defined in the accompanying claims.

What I claim is:

1. Apparatus for controlling the slide movement in a long-bed hydraulic press having two or more symmetrically-disposed slide-actuating rams and related ram advance chambers, the said apparatus comprising a plurality of pumping systems adapted to pump supplies of liquid separately to each of said chambers, adjustable compensating means, adapted for adjustment independently of said plural pumping systems, for effecting compensating variations, during the advance movement of the press slide, in the volume of liquid pumped into said chambers, and an electric control system, adapted to control the adjustment of said compensating means and being responsive to non-parallelism of the press slide, whereby to cause said compensating means to effect compensation in the volume of liquid pumped into said chambers to substantially remedy such non-parallelism.

2. Apparatus for controlling the slide movement in a long-bed hydraulic press having two or more symmetrically-disposed slide-actuating rams and related ram advance chambers, the said apparatus comprising a plurality of pumping systems adapted to pump supplies of liquid separately to each of said chambers, transfer means for transferring liquid, during the advance movement of the press slide, from the said liquid supply of a ram advance chamber located toward one side of the press to the liquid supply of a ram advance chamber located toward the opposite side of the press, and an electric control system, adapted to control the operation of said transfer means and being responsive to non-parallelism of the press slide, whereby to cause said transfer means to transfer sufficient liquid to substantially remedy such non-parallelism.

3. Apparatus for controlling the slide movement in a long-bed hydraulic press having two or more symmetrically-disposed slide-actuating rams and related ram advanced chambers, the said apparatus comprising a plurality of pumping systems adapted to pump supplies of liquid separately to each of said chambers, compensating means comprising pumping apparatus, connected between ram advance chambers at opposite sides of the press slide for effecting compensating variations, during the advance movement of the press slide, in the volume of liquid pumped into said chambers, and an electric control system, adapted to control the operation of said compensating means and being responsive to non-parallelism of the press slide; the said pumping apparatus having flow-controlling means, controlled by said electric system, for controlling the flow of liquid through said pumping apparatus between said chambers, whereby to cause said compensating means to effect compensation in the volume of liquid pumped into said chambers to substantially remedy such non-parallelism.

4. Apparatus according to claim 3, further characterized in that the mentioned flow-controlling means are adapted to control the direction of flow of liquid through said pumping apparatus between said chambers and to vary the volume of such flow.

5. Apparatus according to claim 1, further characterized in that the said electric control system comprises an electric circuit, controlling the adjustment of said compensating means, a switch in said circuit, and switch operating

means adapted to operate said switch in response to non-parallelism of the press slide.

6. Apparatus for controlling the slide movement in a long-bed hydraulic press having two or more symmetrically-disposed slide-actuating rams and related ram advance chambers, the said apparatus comprising a plurality of pumping systems adapted to pump supplies of liquid separately to each of said chambers, compensating means for effecting compensating variations, during the advance movement of the press slide, in the volume of liquid pumped into said chambers, and an electric control system, adapted to control the operation of said compensating means and being responsive to non-parallelism of the press slide, whereby to cause said compensating means to effect compensation in the volume of liquid pumped into said chambers to substantially remedy such non-parallelism, the apparatus being further characterized in that the said electric control system comprises an electric circuit, controlling the operation of said compensating means, a switch in said circuit, and a pair of movable members coacting with the press slide at opposite sides thereof and with said switch, whereby, through said circuit, to control the operation of said compensating means.

7. Apparatus for controlling the slide movement in a long-bed hydraulic press having two or more symmetrically-disposed slide-actuating rams and related ram advance chambers, the said apparatus comprising a plurality of pumping systems adapted to pump supplies of liquid separately to each of said chambers, compensating means for effecting compensating variations, during the advance movement of the press slide, in the volume of liquid pumped into said chambers, and an electric control system, adapted to control the operation of said compensating means, and comprising an electric circuit, controlling the operation of said compensating means, a switch in said circuit, a pair of rotatable shafts, and driving means at each of opposite sides of the press slide, controlled by the movement of the latter and adapted to coact with and separately drive said shafts to degrees which correspond or differ in accordance with the parallelism or non-parallelism of the press slide, the said switch being carried upon and constrained to rotate with one of said shafts, and the other of said shafts having a switch actuator constrained to rotate therewith, the said switch and actuator being in non-coacting relationship during the parallelism of the slide but being adapted to coact with each other to operate said switch in response to relative movement occurring between said shafts upon the departure of the press slide from parallelism, whereby to cause said compensating means to effect compensation in the volume of liquid pumped into said chambers to substantially remedy such non-parallelism.

8. Apparatus according to claim 1, further characterized in that the said compensating means comprise a movable member adapted to control the said compensating variations, and in having driving means coacting with and adapted to actuate said movable member, the said electric control system being adapted to control the said driving means, and, through control of the latter, to control the said compensating means to remedy non-parallelism of the press slide.

9. Apparatus for controlling the slide movement in a long-bed hydraulic press having two

or more symmetrically-disposed slide-actuating rams and related ram advance chambers, the said apparatus comprising a plurality of pumping systems adapted to pump supplies of liquid separately to each of said chambers, compensating means for effecting compensating variations, during the advance movement of the press slide, in the volume of liquid pumped into said chambers, and an electric control system adapted to control the operation of said compensating means and being responsive to non-parallelism of the press slide, the said compensating means comprising a movable member adapted to control the said compensating variations, and a fluid-actuated motor coacting with and adapted to actuate said movable member, the said electric control system being adapted to control the said motor, and, through control of the latter, to cause said compensating means to effect compensation in the volume of liquid pumped into said chambers to substantially remedy such non-parallelism.

10. Apparatus according to claim 1, further characterized in that the said compensating means comprise a movable member adapted to control said compensating variations to a degree corresponding substantially to the degree of movement of said movable member, and in having driving means for moving said movable member, the said driving means having plural, separately controllable stages of operation, and the said electric control system having plural circuits, each responsive to different degrees of non-parallelism of the press slide and adapted to control the mentioned separate stages of operation of said driving means.

11. Apparatus for controlling the slide movement in a long-bed hydraulic press having two or more symmetrically-disposed slide-actuating rams and related ram advance chambers, the said apparatus comprising a plurality of pumping systems adapted to pump supplies of liquid separately to each of said chambers, compensating means for effecting compensating variations, during the advance movement of the press slide, in the volume of liquid pumped into said chambers, and an electric control system, adapted to control the operation of said compensating means, the said compensating means comprising a movable member adapted to control said compensating variations to a degree corresponding substantially to the degree of movement of said movable member, the apparatus having driving means, for moving said movable member, comprising a fluid-actuated motor including a casing, and a piston adapted to reciprocate within said casing, the casing having separate chambers for fluid for causing plural stages of movement of said piston in one direction, and the said electric control system having plural circuits, each responsive to different degrees of non-parallelism of the press slide and adapted to control the supply of fluid to said separate chambers in accordance with such different degrees of non-parallelism of the press slide, whereby to cause said compensating means to effect compensation in the volume of liquid pumped into said ram advance chambers to substantially remedy such non-parallelism.

12. Apparatus according to claim 11, further characterized in that the said casing has such separate chambers for fluid for causing plural stages of movement of said piston in each direction, and in that the said electric control system has plural circuits, each responsive to different

directions and degrees of non-parallelism of the press slide and adapted to control the supply of fluid to said separate chambers in accordance with the direction and degree of non-parallelism of the said slide.

13. Apparatus for controlling the slide movement in a long-bed hydraulic press having two or more symmetrically-disposed slide-actuating rams and related ram advance chambers, the said apparatus comprising a pumping system for each of said ram advance chambers, adjustable compensating means, adapted for adjustment independently of said pumping systems, for substantially equalizing the volume of liquid pumped to each of said chambers during the advance movement of the press slide, a fluid actuated motor coacting with said compensating means for adjusting the latter, and motor control means, responsive to non-uniform advance movement of the press slide and adapted to control the fluid supply to said motor.

14. Apparatus for controlling the slide movement in a long-bed hydraulic press having two or more symmetrically-disposed slide-actuating rams and related ram advance chambers, the said apparatus comprising a pumping system for each of said ram advance chambers, compensating means, comprising a reversible pump connected between ram advance chambers at opposite sides of the press slide for substantially equalizing the volume of liquid pumped to each of said chambers during the advance movement of the press slide, a fluid-actuated motor coacting with said compensating means for operating the latter, and motor-control means, responsive to non-uniform advance movement of the press slide and adapted to control the fluid supply to said motor.

15. Apparatus for controlling the slide movement in a long-bed hydraulic press having two or more symmetrically-disposed slide-actuating rams and related ram advance chambers, the said apparatus comprising a pumping system for each of said ram advance chambers, compensating means for substantially equalizing the volume of liquid pumped to each of said chambers during the advance movement of the press slide, a fluid-actuated motor coacting with said compensating means for operating the latter, and motor control means, responsive to non-uniform advance movement of the press slide and adapted to control the fluid supply to said motor, said motor control means comprising an electric circuit including a switch adapted to be operated in response to non-uniform advance movement of the press slide.

16. Apparatus for controlling the slide movement in a long-bed hydraulic press having two or more symmetrically-disposed slide-actuating rams and related ram advance chambers, the said apparatus comprising a pumping system for each of said ram advance chambers, compensating means for substantially equalizing the volume of liquid pumped to each of said chambers during the advance movement of the press slide, a fluid-actuated motor coacting with said compensating means for operating the latter, and motor control means, responsive to non-uniform advance movement of the press slide and adapted to control the fluid supply to said motor, said apparatus being further characterized in that the said motor is capable of plural stages of operation and in that the motor control means comprise separate electric circuits, adapted to separately control said stages of operation and in that each

of said circuits includes separate switches, each of said switches being adapted to operate in response to different degrees of non-uniform advance movement of the press slide.

17. Apparatus for controlling the slide movement in a long-bed hydraulic press having one or more pairs of slide-actuating rams, the members of which pairs are equidistant from the center of said slide and at opposite sides thereof, and related pairs of ram advance chambers; the said apparatus comprising separate, substantially similar pumping systems for each of said chambers, adjustable compensating means for each pair of chambers, adapted for adjustment independently of said pumping systems, for substantially effecting compensating variations, during the advance movement of the press slide, in the volume of liquid pumped into the paired chambers, and an electric control system, adapted to control the adjustment of said compensating means and being responsive to non-parallelism of the press slide.

18. Apparatus for controlling the slide movement in a long-bed hydraulic press having one or more pairs of slide-actuating rams, the members of which pairs are equidistant from the center of said slide and at opposite sides thereof, and related pairs of ram advance chambers; the said apparatus comprising separate, substantially similar pumping systems for each of said chambers, adjustable compensating means for each pair of chambers, adapted for adjustment independently of said pumping systems, for substantially effecting compensating variations, during the advance movement of the press slide, in the volume of liquid pumped into the paired chambers, a fluid actuated motor coacting with said compensating means for adjusting the latter, and motor control means, responsive to non-uniform advance movement of the press slide and adapted to control the fluid supply to said motor.

19. Apparatus for controlling the slide movement in a long-bed hydraulic press having two or more symmetrically-disposed slide-actuating

rams and related ram advance chambers, the said apparatus comprising a plurality of pumping systems adapted to pump supplies of liquid separately to each of said chambers, compensating means for effecting compensating variations, during the advance movement of the press slide, in the volume of liquid pumped into said chambers, an electric operating circuit including a safety switch, for controlling the said advance movement, an electric compensation-control circuit including a control switch, for controlling the operation of said compensating means, and a pair of movable members, adapted to derive movement relatively to each other, in response to non-uniform advance movement of the press slide, through coaction with opposite sides of the said slide, one of said movable members having a portion constituting a switch actuator and the other of said members having said control switch and said safety switch fixed thereon along the path followed by said actuator during such relative movement, the said control switch being adapted to be operated by said actuator upon a predetermined degree of tilting of the press slide and the said safety switch being adapted to be operated by said actuator upon tilting of the press slide beyond a predetermined degree of tilting, whereby to cause said operating circuit to stop the advance movement of the press slide.

20. Apparatus for controlling the slide movement in a hydraulic press having an electric circuit adapted to control the closing movement of the press slide, the said apparatus comprising a pair of movable members, adapted to derive movement relatively to each other, in response to non-uniform advance movement of the press slide, through coaction with opposite sides of the said slide, and a switch, in said circuit, carried upon one of said members, a portion of the other of said members being adapted, during such relative movement, to engage and operate said switch whereby to cause said electric circuit to stop the movement of the press slide.

EARL CANNON.

CERTIFICATE OF CORRECTION.

Patent No. 2,353,388.

July 11, 1944.

EARL CANNON.

It is hereby certified that error appears in the printed specification of the above numbered patent requiring correction as follows: Page 9, second column, line 55, claim 15, after the word "movement" insert --of opposite sides--; and that the said Letters Patent should be read with this correction therein that the same may conform to the record of the case in the Patent Office.

Signed and sealed this 22nd day of August, A. D. 1944

Leslie Frazer

(Seal)

Acting Commissioner of Patents.
